ATTY

UNITED STATES PATENT OFFICE.

HUNTINGTON MALARKEY, OF CHICAGO, ILLINOIS.

DOOR CONSTRUCTION.

Application filed November 24, 1924. Serial No. 751,898.

To all whom it may concern:

Be it known that I, HUNTINGTON MALARKEY, a citizen of the United States, and a resident of Chicago, in the county of Cook and State of Illinois, United States of America, have invented new and useful Improvements in Door Constructions, of which the following is a specification.

The present invention relates to the structural features of a door, and has particularly to do with the joinder of several elements thereof, the construction of such elements, the manner in which said elements are correlated for the purpose of reducing manufacturing costs upon a finished door.

Among the objects of the invention are the following:—

An improvement in door construction whereby a new and improved type of mullion is used, making the door such that it is practically impervious to moisture notwithstanding the severity of its exposure to the elements;

An improvement in the method of uniting said mullion with the rails of a door and forcing it into interlocking association with the panels thereof;

The combination in a door, of a mullion and rails in association with the panels intermediate said mullion and the stiles of said door whereby said mullion and said panels are rendered proof against the effects of weather;

An improved construction whereby the mullion or mullions of a door and the panels thereof are locked into position by a wedge construction, rendering the door structure thoroughly substantial and wholly weatherproof.

These, and such other objects as may hereinafter appear, are obtained by the novel construction of the several elements which constitute a door embodying said invention, the arrangement of said elements, and the combination thereof in the assembly of said door. The accompanying single sheet of drawing illustrates a single embodiment of the invention and should be referred to in connection with a description of the invention hereinafter given.

In said drawing:—

Figure 1 is a front or rear elevation of a door embodying the invention.

Figure 2 is a transverse section on the line 2—2 of Figure 1, looking in the direction of the arrows.

Figure 3 is a fragmentary vertical section on the line 3—3 of Figure 1, looking in the direction of the arrows.

Figure 4 is a fragmentary vertical section on the line 4—4 of Figure 1, looking in the direction of the arrows.

Figure 5 is a fragmentary transverse section through one stile and a portion of the bottom rail of the door on the line 5—5 of Figure 1, looking in the direction of the arrows.

Like reference characters are used to designate similar parts in the drawing and in the description which follows.

Examination should first be made of Figure 1. Numerals 10 and 11 are used to designate the stiles of a door embodying the invention; the molding on the inner edges of said stiles being formed upon a sticking machine common in the art. Arranged transversely of and engaging stiles 10 and 11 are a plurality of rails, the uppermost or top one of said rails being designated 12, the intermediate rail being called the lock rail and designated 13, and the lowermost rail being generally named hereinafter as bottom rail 14. Between said top rail 12 and said lock rail 13 and stiles 10 and 11 are bars and muntins, designated 16 and 17. The stiles 10 and 11 and the rails 12 and 13 may be provided with rabbets for glass as is usual in the art.

For the purpose of securely joining stiles 10 and 11 to the rails 12, 13 and 14, a plurality of dowels 18 may be employed. Any other suitable fastening means may be used when desired.

A vertically paneled door such as is here illustrated, is always preferred in architectural designing, for the reason that vertical panels lend an artistic effect. Doors which are not subject to exposure to the elements are almost invariably vertically paneled because a longitudinal disposition of panels has a higher artistic merit and is more pleasing to the esthetic nature than a door having transversely arranged panels.

In doors comprising a plurality of panels longitudinally arranged, mullions are disposed intermediate the lock rail and bottom rail thereof. In conventional door construction, such mullions are arranged so that they are flush with the lock and bottom rails of the door and are coextensive therewith in respect to thickness of material. Such a construction as this, however, has proved

wholly unsuited for exposed doors upon buildings such as garages and the like because rain and snow cause an opening of the joints between such mullions and the rails between which such mullions are disposed, producing a destructive disturbance with respect to the panels in association with said mullions, and eventually rendering the door unfit for use because of opened joints there in.

10 The present invention is to overcome this objection to an out-of-door door having longitudinally disposed mullions and for the added purposes of improving the artistic effect 15 obtainable through the agency of a mullion, and to generally improve door construction.

Reference again should be had to Figure 1, and additionally, to Figures 2, 3 and 4. In the door illustrated in Figure 1 but two 20 panels are shown, but there may be any number of panels according to the width of a door. Between each two adjacent panels is a mullion, designated in the accompanying drawing as 19. Said adjacent panels are 25 designated 20.

For the purpose of seating mullion 19 intermediate lock rail 13 and bottom rail 14, said rails are each provided with a plowed groove, the central portion 21 of the groove 30 being of greater depth than the side portions 22 thereof. Mullion 19 is of a thickness coextensive with the wider portion 22 of said grooves, and is disposed therein after assembly with respect to panels 20. Stiles 35 10 and 11 are provided with longitudinal grooves 23 and 24 in the molding on their inner edges and mullion 19 has opposite longitudinal grooves 25 and 26 to receive therein the edges of panels 20, said edges of panels 20 extending into the deep section 21 of the plowed grooves in lock rail 13 and bottom rail 14.

In this assembly, spaces are left intermediate the surface of each panel 20 and the 45 vertical margin of groove 22 in both the lock rail 13 and the bottom rail 14, which spaces are substantially coextensive with the width of the shallow groove sections 22. These pockets or unfilled spaces exist at both 50 the top and bottom of panels 20 and upon both sides thereof, four of such spaces being formed in relation to each panel 20. Into these pockets are subsequently forced wedge members 27, each of said wedge members 55 comprising a wedge shaped stick having its one end shaped to coincide with the contour of the molding upon the stiles 10 and 11 and

its other end with the edge of mullion 19 extending from the grooves 25 and 26 to the exposed flat transverse surface thereof. 60 Glue may be used to secure wedges 27, or any other desirable affixing means.

In Figure 5, a detail in section of the dowel construction of the door is disclosed.

It is quite manifest from the foregoing 65 that the embodiment of the invention here illustrated is but one of the many forms which the invention may assume, and it is not the purpose of this application to limit the invention to such single structure but, 70 on the contrary, the measure of the invention is to be found in the claims hereto appended. Such invention resides in a new form of mullion as disclosed, in the manner of associating such mullion with a door, and in the 75 use of wedge members, or their equivalent, in conjunction with such mullion for the purpose of securing panels of the door in rigid position and wholly free from the rampages of weather. It is instantly apparent that a more artistic door may be produced by the use of a depressed mullion 80 which is here disclosed than may be had by the usual flush mullion construction.

I claim:—

1. A door comprising stiles, rails, panels, and a mullion intermediate said panels, said rails being transversely grooved to provide a seat for said panels and mullion, and in which said rails have a continuous groove of two depths, said panels being seated in said grooves at one depth and said mullion being seated therein at the other depth thereof. 90

2. A door comprising stiles, rails having arranged therein a groove of two depths, 95 panels in the deeper section of said grooves, a mullion intermediate said panels and seated in the shallow section of said grooves, and locking strips also in said shallow section and engaging said panels.

3. In a door, stiles, rails having a wide groove therein, panels in the central portion of said grooves, and wedge members in said grooves and upon each side of said panels. 100

4. A door comprising vertical stiles, transverse top, lock and bottom rails, panels intermediate said lock and bottom rails, a mullion separating said panels, and locking wedges on opposite sides of said panels, said lock and bottom rails being grooved to seat 105 said panels at one depth, and said mullion and said locking wedges at another depth. 110

HUNTINGTON MALARKEY.
